The ornamental design for a strap corner, as shown and described.

DESCRIPTION

FIG. 1 is a top perspective view of a strap corner showing our new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a left side elevational view thereof;

FIG. 7 is a right side elevational view thereof; and,

FIG. 8 is a top perspective view thereof, showing the design illustrated with environmental structures, with the design mounted on a corner of a load equipment and partially covered by a securing strap.

The ornamental design which is claimed is shown in solid lines in the drawings. The stippled lines in FIGS. 1 through 7 are included for the purpose of illustrating features of unclaimed portions of the strap corner and form no part of the design.

The broken lines represent portions of the invention and environment of use and form no part of the claim.

1 Claim, 8 Drawing Sheets(56)
